UNITED STATES PATENT OFFICE.

GEORGE DAWSON HOOD, OF TORONTO, ONTARIO, CANADA.

FUEL CABINET.

1,419,259.

Specification of Letters Patent. Patented June 13, 1922.

Application filed December 8, 1919. Serial No. 343,218.

To all whom it may concern:

Be it known that I, GEORGE DAWSON Hood, a subject of the King of Great Britain, and resident of 92 Fairview Ave., in the 5 city of Toronto, county of York, Province of Ontario, in the Dominion of Canada, have invented certain new and useful Improvements in Fuel Cabinets, of which the following is a specification.

10 The invention relates to improvements in fuel cabinets, as described in the present specification and shown in the accompanying drawing that forms a part of the same.

The invention consists essentially of the 15 novel features of construction whereby a cabinet divided into compartments for various purposes is provided with a coal receptacle accessible from the top of said cabinet and having a comparatively small delivery mouth adapted to automatically feed 20 a predetermined quantity of coal to a delivery chamber located therebelow.

The objects of the invention are to provide a coal receptacle in which the coal will 25 be gradually fed to the delivery chamber without undue agitation and thus reduce to a minimum the dust rising therefrom, to provide a fuel cabinet adapted for the purpose of containing household articles of various 30 kinds and generally to provide a fuel cabinet which will be neat of appearance, inexpensive to construct, durable and efficient.

In the drawing Figure 1 is a perspective 35 view of the cabinet open.

Figure 2 is a plan view with the top open.

Figure 3 is a vertical section through the cabinet.

Like numerals of reference indicate corresponding parts in the various figures.

Referring to the drawing 1 is the casing which is preferably of rectangular form and is provided with an opening 2 in the top thereof adapted to be closed by a lid 3, and 45 an opening 4 in the front thereof adapted to be closed by a door 5, said front opening being located slightly below the longitudinal centre of the cabinet and terminating at its lower end considerably short of the bottom

50 of the cabinet. The upper portion of the cabinet is adapted to serve as a container for coal or other fuel and is provided with a substantially funnel shaped bottom comprising a rearwardly and downwardly extending front wall 6 terminating short of

the rear wall of the cabinet, and inwardly converging side walls 7 and 8 respectively meeting opposite side edges of said front wall 6 and forming a comparatively small delivery mouth 9.

60 The front wall 6 of the fuel container or chute is shown in the drawing as being supported from the lower end of an inset or lining 10 of wood secured to the front wall of the cabinet but it must of course be understood that said wall 6 as well as the side walls 7 and 8 may be secured in any desired manner to the cabinet frame.

11 is the chamber located beneath the fuel container and adapted to receive the fuel 70 from the chute for delivery, said chamber 11 being composed of a flooring 12 extending from front to rear of the cabinet on a level with the lower edge of the front opening 4 and of substantially the same width 75 as the opening in the lower end of said chute, and side walls 13 and 14 vertically arranged between said flooring 12 and the walls of the chute of the fuel container.

80 It will thus be seen that a continuous passage for the fuel entirely separated from the remaining compartments is provided between the top of the cabinet and the front opening from which it is adapted to be taken thus making it impossible for the dust to 85 reach the interior of said other compartments. The space between the floor of the cabinet and the floor 12 of the chamber 11 is adapted for use for storing small articles while the space between side walls of the 90 cabinet and the side walls 13 and 14 respectively may be utilized for storing brushes, brooms and like articles.

In the use of this invention the fuel is 95 deposited through the top of the cabinet and as the delivery mouth is much smaller than the opening in the top only a small quantity of fuel is allowed to drop on to the floor of the delivery chamber and as this is removed a further quantity drops down to take 100 its place and in this manner a small amount of fuel is always accessible from the front of the cabinet.

What I claim is:

105 The combination in a fuel cabinet substantially rectangular in shape, having top and front openings, closures for said openings, vertical partitions dividing the floor space of cabinet into three compartments, a chute supported upon the top edges of said parti- 110

tions and securely affixed to and supported from the walls of the cabinet in a manner to form an air tight joint, the delivery end of said chute terminating at rear of central compartment and thereby forming a fuel chamber in said compartment, and having compartments adjoining said fuel chamber

and having air tight joints between said compartments and fuel chamber.

Signed at the city of Toronto, this 12th 10 day of November, 1919.

GEORGE DAWSON HOOD.

Witness:

W. G. HAMMOND.
